STAPLE SUPPORT SLIDE AND FEED MEANS
FOR STAPLING MACHINES

Samuel Segal, New York, N. Y., assignor to Wilson-Jones Company, Chicago, Ill., a corporation of Massachusetts

Application May 1, 1951, Serial No. 223,870

7 Claims. (Cl. 1—3)

1

This invention relates to a staple support slide and feed means for stapling machines, and particularly to a staple support slide having a feeding mechanism that will enable the last staple in the machine to be driven through the exit channel.

It is a common disadvantage of many stapling machines that the staple feeding mechanism can not move close enough to the exit channel to feed the last few staples, with the result that the machine must be re-loaded before it is entirely empty. In many stapling machines the necessity of re-loading the machine before it is entirely empty is particularly annoying because the staple support slide will accommodate only one strip of staples, and, since the staples come in strips of standard length, some of the staples must be removed from the strip being inserted into the machine.

It is an object of this invention to provide a staple support slide with a feeding mechanism capable of feeding the last staple from the slide. Other objects and advantages of the invention will become apparent upon reading the following description, taken in conjunction with the accompanying drawings, in which:

Figure 1 is a perspective view of a stapling machine embodying the invention;

Figure 2 is a perspective view of the stapling machine with the body portion swung around its pivot;

Figure 3 is an inverted perspective view of the staple support slide with the pusher mechanism in its extreme forward position;

Figure 4 is a cross sectional view, taken generally along the line 4—4 of Figure 3, but showing the staple support slide in position in the body portion of the stapling machine;

Figure 5 is a fragmentary longitudinal sectional view, taken along the line 5—5 of Figure 4;

Figure 6 is a fragmentary longitudinal sectional view, taken along the line 6—6 of Figure 4;

Figure 7 is a fragmentary longitudinal sectional view, taken along the line 7—7 of Figure 6;

Figure 8 is a bottom perspective view of the body portion of the stapling machine, with the staple support slide positioned therein, parts of the stapling machine and staple support slide being broken away to facilitate illustration of the staple feeding mechanism;

Figure 9 is a top elevational view of the staple support slide with the pusher mechanism in its extreme forward position, and showing, in dotted lines, the position of the pusher mechanism immediately after a strip of staples has been positioned on the slide;

Figure 10 is a detailed perspective view of the staple pusher mechanism; and

Figure 11 is a detail perspective view of a modified embodiment of the pusher mechanism.

2

In the drawings, the reference numeral 2 indicates the base portion of a stapling machine having a body portion 3 pivotally secured thereto, as indicated at 4. The body portion is provided with a head 5 mounted on a plunger 6 for driving the staples 7 which are mounted on a staple support slide 8 fitting in a recess 9 in the bottom of the body portion 3. The recess 9 is defined by the side walls 10 and 11, and the front wall 12 of the body portion. The rear end 10 of the recess 9 is left open to permit the staple support slide 8 to be inserted into and removed from the recess. The side walls 10 and 11 are provided with longitudinally extending recesses 13 and 14, respectively, as shown in Figure 4. The staple support slide 8 comprises a channel shaped member having a top wall 15, side walls 16 and 17, and an end wall 18. A latch 19 pivotally secured to end wall 18 cooperates with notches in the side walls 10 and 11 to retain the staple support slide against longitudinal displacement in the stapling machine. The staple support slide 8 also has laterally extending flanges 20 and 21 fitting in recesses 13 and 14, respectively, to hold it in proper position and to prevent vertical displacement of the slide relative to the stapling machine. The forward end of the staple support slide is spaced slightly from the end wall 12, and a plate 22 (Fig. 8), having rearwardly extending projections 23 and 24, is positioned between the end wall 12 and the foremost position of the staple support slide to define an exit channel 25 (Fig. 6) through which the staples 7 are individually driven by the plunger 6 in response to force applied downwardly against the head 5.

The feeding mechanism comprises a feed block 26 mounted on a rod 27, a spring 28 for propelling the feeding block forwardly and a pressure plate 29. The rod 27 has one end supported by a lip 30 (Fig. 8) struck from the stop wall 15 of the staple support slide, and its other end supported by end wall 18. One end of the rod is provided with an enlarged head, and the other end is enlarged, as indicated at 31, after the rod is inserted into position. The feed block 26 is bored, as indicated at 32 (Fig. 10), so that it can slide longitudinally on the rod 27. The spring 28 encircles the rod 27 and is positioned between end wall 18 and pressure plate 29 which is also slidable on the rod 27.

The opposite edges of feed block 26 are provided with recesses 33 and 34 in which feed fingers 35 and 36 are pivoted, as indicated at 37 and 38, respectively. Feed fingers 35 and 36 are duplicates, except that they are reversed, so only one of them will be described. The forward end of each feed finger is bifurcated to form prong-like portions 39 and 40. The side walls 16 and 17 of the staple support slide 8 are each provided with a longitu-

dinally extending slot 41. The legs of the staples positioned on the staple support slide straddle the side walls 16 and 17, and extend past the slot 41. The portions 39 of the feed fingers are adapted to project through the slot 41 to the rear of the staples and are urged against the legs of the rear-most staple by the spring 28 to propel the staples forwardly towards the exit channel (see Fig. 8). These portions 39 are extended forwardly of the feed block far enough so that their forward ends are flush with the end of the staple support slide when the feed block is in its forward position (see Figs. 6 and 7). This arrangement of the feed fingers makes it possible to feed the last staple from the machine even though the feed block can not be moved forwardly past the lip 30. The front end of each portion 40 of the feed fingers is curved, as indicated at 42, to abut one of the inside walls of the slide 8 to prevent it from entering slot 41, and thereby limits the outward lateral movement of the feed fingers.

The lip 30 is positioned as close as possible to the forward edge of the staple support slide so that it will not be necessary to extend the portions 39 of the feed fingers so far as to make them too weak to perform their intended function. The cut out in the top wall of the staple support slide, from which the lip 30 is formed, will naturally weaken the front edge of the top wall. This front edge portion of the top wall is strengthened by a transversely extending reinforcing ridge 43 (Fig. 5) which is embossed in the top wall between the lip 30 and the front edge of the top wall.

In loading the stapling machine, a plurality of staples adhered together in a strip of standard length is inserted into the recess 9 through the open rear end of the recess with the legs of the staples straddling the side walls 16 and 17 of the staple support slide 8. It has been found inconvenient to retract the feed block 26 and to position the strip of staples 7 forwardly of the feed block. Accordingly, it is customary to position the new strip of staples on the slide when the feed block is in its forward position, and to then retract the feed block. When the feed block is retracted the rear edges of the feed fingers 35 and 36 engage the foremost staple and push the whole strip of staples towards the rear end of recess 9. The user loading the machine places his thumb over the rear edge of recess 9 and thereby prevents the staples from being pushed out of the recess. The thumb pressure against the rearmost staple causes the fingers 35 and 36 to collapse inwardly as the feed block is retracted until the feed fingers are moved past the rearmost edge of slots 41 so that the extensions 39 are confined by the inside of walls 15 and 16. The machine is then tilted to make the staples slide towards the front end of the machine. The feed block is then released and is moved forwardly by spring 28. When the feed fingers move forwardly far enough to register with the slots 41 they move outwardly through the slots 41 and then engage the legs of the rearmost staple to propel the staples forwardly towards the exit channel. This loading procedure requires that the extensions 39 must be retracted laterally at the forward end of the slots 41 so that the feed fingers can be positioned entirely within the space between the legs of the staples, and then retracted longitudinally until the forward edges of the extensions 39 are confined by the inside of walls 15 and 16. It is necessary that the extensions 39 of the feed fingers must extend to the forward edge of the staple slide when the feed block is in its forward posi-

tion in order to feed the last staple to the exit channel. The slot 41 does not extend to the forward edge of the staple slide and therefore when the feed block is in its forward position the feed fingers can not be retracted laterally because the inside edges of the extensions 39 would engage the portions 16' and 17' of side walls 16 and 17 which lie between the forward end of slot 41 and the forward edge of the side walls. The feed block must be retracted far enough to permit the extensions 39 to clear the portions 16' and 17' of the side walls 16 and 17 defining the forward edges of slots 41 before the feed fingers can be retracted laterally into the slots. The length of slots 41 must therefore be great enough to extend past the rear end of the strip of staples a distance great enough to permit the feed fingers 35 and 36 to move outwardly through slots 41 to engage the legs of the rearmost staple at the rear end of the slide when the forward end of the strip of staples is positioned in its foremost position.

The staples 7 are propelled forwardly by feed block 26 which is urged forwardly by the spring 28. When the feed fingers 35 and 36 are retracted within slots 41, their rearmost portions 44 and 45 (Fig. 6) project slightly beyond the rear edge of the feed block 26. The pressure plate 29, which is interposed between the rear edge of the feed block and the spring 28, is pressed against the rear edge of the feed block by the force of the spring. The pressure of plate 29 against portions 44 and 45 of the feed fingers forces the feed fingers outwardly through the slots 41 so as to align the forward edges of extensions 39 with the legs of the staples 7. When the feed block is retracted against the force of spring 28, the feed fingers 35 and 36 are retracted laterally by engagement of the rear side of the feed fingers with the legs of the foremost staple 7 against which they are pressed. The feed fingers are pivoted very sensitively so that only a slight pressure is necessary to move them in either direction.

In the embodiment of Figure 11, the pressure plate 29 is replaced by a channel shaped pressure plate 46 which has one wall 47 positioned against the rear edge of feed block 26 so that it acts in the same manner as the pressure plate 29. Another wall 48 of pressure plate 46 is spaced from wall 47 by a connecting wall 49 which is slightly longer than feed block 26. The wall 48 is cut away at its outer edges, as indicated at 50, to provide clearance for the feed fingers. When the staples are being propelled forwardly there is no difference in operation between wall 47 of pressure plate 46 and pressure plate 29. When it is desired to retract the feeding mechanism, finger pressure applied to wall 48 moves wall 47 out of contact with the rear edge of the feed block 26, so that when the feed block is moved rearwardly the feed fingers 35 and 36 are free to retract laterally with a minimum amount of pressure exerted against them because the spring 28 does not urge the fingers outwardly through pressure against wall 47 as it does with pressure against plate 29 in the previously described embodiment. As in the embodiment of Figures 1 to 10, the user may hold his thumb over the open rear end of recess 9 to prevent the staples from being pushed out of the recess when the feed block is retracted.

Although I have described two preferred embodiments of my invention in considerable detail, it will be understood that the description thereof is intended to be illustrative, rather than restric-

tive, as many details may be modified or changed without departing from the spirit or scope of the invention. Accordingly, I do not desire to be restricted to the exact structure described, except as limited by the appended claims.

I claim:

1. In a magazine for stapling machines, a body portion, a staple support slide, a feeding mechanism comprising a feed block movable longitudinally relative to said staple support slide, means limiting the forward movement of said feed block relative to the staple support slide, and a pair of feed fingers pivotally mounted in said feed block, each of said fingers having a portion extending forwardly a distance sufficient to position said portions flush with the forward edge of said slide when said feed block is in its forward position.

2. In a magazine for stapling machines, a body portion, a staple support slide, a feed block, spring means for moving said feed block forwardly relative to said staple support slide, means limiting the forward movement of said feed block, and a pair of feed fingers pivoted to said feed block, each of said fingers extending forwardly of said feed block to a position flush with the forward edge of said slide when said feed block is in its forward position.

3. In a magazine for stapling machines, a body portion, a staple support slide, a feed block movable longitudinally relative to said staple support slide, a pair of feed fingers pivoted to said feed block to move inwardly and outwardly relative to said block, a portion of each of said feed fingers projecting slightly rearwardly from said feed block when said feed fingers are in their innermost positions, a pressure plate engaging the rearwardly projecting portions of said feed fingers, and spring means urging said pressure plate forwardly to engage the rear edge of said feed block and to move said feed fingers laterally to their outermost positions, said pressure plate having a front wall spaced forwardly of said feed plate, whereby finger pressure applied to said front wall to move said feed block rearwardly of said staple support slide moves said pressure plate out of engagement with the rear edge of said feed block and removes the pressure against the rearwardly projecting portions of said feed fingers so that they may move laterally inwardly without resistance.

4. In a magazine for stapling machines, a body portion, a staple support slide, a rod extending longitudinally of said slide, a channel shaped pressure plate mounted on said rod, said pressure plate having parallel front and rear walls spaced longitudinally on said rod, a feed block slidably mounted on said rod between said front and rear walls, said feed block being of less length than the longitudinal distance between the front and rear walls of said pressure plate, a spring embracing said rod and exerting pressure against the rear wall of said pressure plate to force it into engagement with the rear edge of said feed block, finger pressure on the front wall of said pressure plate being effective to move said rear wall out of engagement with the rear edge of said feed block before said feed block can be slid rearwardly relative to said slide, and a pair of feed fingers pivotally mounted in said feed block, said feed fingers having portions extending rearwardly of said feed block so that the feed fingers are held in their outermost positions by pressure of said rear wall when said rear wall is in engagement with the rear edge of said feed block.

5. In a magazine for stapling machines, a body portion, a staple support slide, a feed block slidably mounted in said staple support slide, a pressure plate having front and rear walls straddling said feed block, said pressure plate being longer than said feed block, spring means urging the rear wall of said pressure plate into engagement with the rear edge of said feed block, finger pressure on the front wall of said pressure plate being effective to move said rear wall out of engagement with the rear edge of said feed block before said feed block can be slid rearwardly relative to said staple support slide, and a pair of feed fingers pivotally mounted in said feed block, said feed fingers having portions extending rearwardly of said feed block so that the feed fingers are held in their outermost positions by pressure of said rear wall when said rear wall is in engagement with the rear edge of said feed block.

6. In a magazine for stapling machines, a body portion, a staple support slide, a feed block slidably mounted in said staple support slide, a lip projecting from said slide, said lip preventing forward movement of said feed block beyond a predetermined point spaced rearwardly from the forward edge of said slide, a pressure plate having front and rear walls straddling said feed block, said pressure plate being longer than said feed block, spring means urging the rear wall of said pressure plate into engagement with the rear edge of said feed block, finger pressure on the front wall of said pressure plate being effective to move said rear wall of the pressure plate out of engagement with the rear edge of said feed block before said feed block can be slid rearwardly relative to said slide, and a pair of feed fingers pivotally mounted in said feed block, said feed fingers having portions extending rearwardly of said feed block when the fingers are in their innermost positions, so that the feed fingers are held in their outermost positions by pressure of said rear wall against the rearwardly projecting portions of the fingers when said rear wall is in engagement with the rear edge of said feed block, the forward ends of said feed fingers being flush with the forward edge of said slide when said feed block is in its forward position.

7. In a magazine for stapling machines, a staple support slide adapted to receive a strip of staples of predetermined overall length, said slide comprising a channel shaped member having a top wall, side walls, a rear end wall, and a lip projecting from said top wall, each of said side walls being provided with a longitudinally extending slot, said lip being spaced rearwardly from the front end of said channel member and being substantially parallel to said rear end wall, a rod having one end supported by said rear end wall and its other end supported by said lip, a feed block mounted on said rod, said feed block being slidable between said rear end wall and said lip, and a pair of feed fingers pivotally mounted in said feed block, each of said feed fingers being bifurcated, said fingers being movable outwardly to project one portion of each finger through said slot, said projecting portion of each finger being flush with the front end of said slide when said feed block is positioned against said lip.
